UNITED STATES PATENT OFFICE.

STRAUD K. WOOD, OF HUTCHINSON, KANSAS.

CAR-IDENTIFYING MEANS.

Application filed July 7, 1923. Serial No. 650,101.

To all whom it may concern:

Be it known that I, STRAUD K. WOOD, a citizen of the United States, and resident of Hutchinson, Reno County, State of Kansas, ⁵ have invented a certain new and useful Improvement in Car-Identifying Means, of which the following is a complete specification.

This invention relates to motor car owner-¹⁰ ship identifying means, and more especially to a device for permanent display in a conspicuous place on a motor car, containing the name of the licensing State, the date of the license, the make of the car, the number of ¹⁵ the engine, the signature of the owner and the owner's address, it being contemplated that a card containing corresponding matter must be carried by the owner, who may be called on for its production by the proper ²⁰ county or municipal authorities, if any question as to ownership of the car arises, the failure of the driver of the car to produce such card or the failure of his signature to correspond to that on the card, being an ²⁵ occasion for investigation and for arrest unless the matter is satisfactorily explained. It will be apparent that through State and national use of means of the character mentioned, the possession of stolen cars will be ³⁰ precarious, the sale of such cars made difficult, the transfer of licenses from one car to another hazardous, and the tracing of stolen cars will be facilitated.

With these objects in view the invention ³⁵ consists in certain novel and useful features of construction and organization of parts as hereinafter described and claimed; and in order that it may be readily understood, reference is to be had to the accompanying ⁴⁰ drawing, in which:

Figure 1 is a fragmentary face view of a portion of an automobile wind-shield, and illustrates a device embodying the invention ⁴⁵ detachably secured thereto.

Figure 2 is an enlarged perspective view of a device embodying the invention.

Figure 3 is an enlarged section on the line ⁵⁰ III—III of Figure 1.

Figure 4 is an enlarged section on the line ⁵⁵ IV—IV of Figure 2.

In carrying out the invention, it is contemplated that the identifying means may be displayed at any convenient point, but it is preferred that it be located on the wind- ⁶⁰ shield, as shown.

Referring now to the drawing, where like parts are correspondingly identified in all of the figures, 1 represents a rectangular frame of channel shape and adapted to receive and retain a pair of glass plates 2, one of said plates forming a backing for the frame and the other plate, a front window.

One end of the frame 1, is formed with a longitudinally-extending slot 3, through which an identification card 4 may be readily inserted or removed, said card being provided on its face with indicia indicating the State licensing the car, the engine number of the car, the make of the car and the owner's address and signature. Secured to ⁶⁵ one edge of the frame and projecting downwardly is a stiff flange 5, a flange 6 of corresponding character projecting laterally from one of the side edges of the frame, and both of said flanges are adapted to be forced ⁷⁰ into the soft metal in which an automobile wind-shield glass is customarily set, although it will be apparent that the frame may be secured to any other part of the car. The flange 5 is split transversely, as illustrated in Figure 2, to produce a plurality ⁷⁵ of fingers 7, and one or more of said fingers are bent upwardly to close the slot 3 and retain the card in proper position between the panes of glass 2, as will be readily understood.

The frame is adapted to be positioned, illustrated, in the lower right hand corner of the wind-shield, its flanges 5 and 6 being forced into the soft metal of the windshield ⁸⁰ setting, and in order to aid in maintaining it in position, and also to prevent vibration from effecting a bodily shifting movement of the frame to the left, a suitable spring clasp 8 is secured to one edge of the frame ⁸⁵ and is adapted to be hooked over and embrace the side frame member 8^a of the wind-shield.

To prevent the panes of glass 2 from rattling against each other, the opposite longitudinal side edges of the frame are formed at convenient points with a pair of openings ⁹⁰ 9, the side edges of said openings being in-turned as at 10 to provide abutments for the opposing faces of the glass panes. The ⁹⁵ lips 10, thus formed, serve to retain the glass plates in position and spaced apart so that the card 4 may be readily inserted or removed from position.

It is to be understood that the card 4 after ¹⁰⁰ 110

being placed in the frame and the frame secured on the car, is not removed until the car changes owners, or at the end of a license period, when the frame is removed, the ears 7 are bent downwardly and the card withdrawn. A new card is now inserted and the ears 7 are again bent upwardly to close the slot against the accidental displacement of the card. A plurality of the ears 7 are provided as the twisting or bending of the ears may lead to their severance from the frame.

From the above description it will be apparent that I have produced a device of the character described which possesses all the features of advantage set forth as desirable; and while I have described and claimed the preferred embodiment of the same, I reserve the right to make all changes properly falling within the spirit and scope of the appended claims:

I claim:

1. A card display frame having a slot at one end, a backing member in said frame, a transparent front member therefor, means

spacing said back and front members from each other, and a securing flange projecting from the end of said frame adjacent said slot.

2. A card display frame having a slot at one end, a backing member in said frame, a transparent front member therefor, means spacing said back and front members from each other, and a securing flange projecting from the end of said frame adjacent said slot, said flange being split transversely to provide ears adapted to be bent upwardly to close said slot.

3. A card display frame having a slot at one end, a backing member in said frame, a transparent front member therefor, means spacing said back and front members from each other, a securing flange projecting from one end of said frame, and a resilient spring clasp secured to and projecting from one end of the frame.

In witness whereof I hereunto affix my signature.

STRAUD K. WOOD.
